U.S. Cl. Plt.—78

1 Claim

This invention relates to a new and distinct variety of chrysanthemum plant characterized by its floriferousness, large blossom size and compact growth habit.

My new plant was first discovered as a seedling in a planting of chrysanthemums derived from a mutation of an unknown variety. The latter plant was approximately four and one half feet in height and bore 3" blooms. The mutation was generally similar to its parent plant, but bore 6" blooms. The instant variety was selected for propagation and further observation since it retained the 6" blossom size but had a neater, more compact growth habit. I have propagated my new variety by cuttings, which propagations retain the characteristics of the original seedling.

Detailed description

Parentage: Unknown

Classification: Decorative

2

Height: 26 inches without pinching
Blooming period October 15 in Santa Barbara, Calif.
Blossom:

Size.—5-7 inches.

Stem.—Wiry, erect, few side buds.

Form.—Decorative, peony, high-crested.

Color.—Creamy yellow center shading to almost pure white outer petals.

Petals.—Texture—good, long lasting.

10

Plant

Form: Upright, compact, generally not branching.
Growth: Sturdy, wiry.

15 Foliage: Deep green, abundant, crinkled, average texture.

Hardiness: Unknown.

I claim:

20 1. A new variety of chrysanthemum plant substantially as shown and described, characterized by a peony-form blossom and compact growth.
